UNITED STATES PATENT OFFICE.

DENNIS X. COAKLEY, OF HAVERHILL, MASSACHUSETTS, ASSIGNOR OF ONE-HALF TO
JOE W. BEAN, OF HAVERHILL, MASSACHUSETTS.

DRINKING-FOUNTAIN.

1,034,384.

Specification of Letters Patent. Patented July 30, 1912.

Application filed October 17, 1910. Serial No. 587,594.

To all whom it may concern:

Be it known that I, DENNIS X. COAKLEY, residing at Haverhill, in the county of Essex and State of Massachusetts, have invented 5 an Improvement in Drinking-Fountains, of which the following is a specification.

This invention relates to certain improvements in that class of drinking-fountains known as "bubblers", in which a jet of 10 water is directed vertically, so that a person may drink from the crest of the stream, the nozzle being frequently, although not necessarily, arranged in a basin which catches the water as it flows from the nozzle and 15 holds it at a level which is slightly above the upper end of the nozzle, so that the force of the jet is, to a degree, arrested, and the crest of the stream made more uniform. When these devices are used in schools, the 20 children are likely to play with the flowing water by placing a finger on the end of the nozzle, so that a forcible stream will be thrown horizontally from the device. This difficulty has been obviated to an extent by 25 providing outlet ports in the supply-pipe, adjacent the jet, but, with this arrangement, when the device is used in places where it is desired that the water run constantly, it occasions a large loss of water.

30 The principal object of my invention is to provide a device of the above described character which is so constructed that it will be impossible for the water to be thrown horizontally by obstructing the nozzle which 35 throws up the stream and which will be so arranged that there will be no unnecessary waste of water.

A further object of my invention is to 40 provide a device of the above described character which shall be simple in construction and sufficiently durable to withstand the usage to which it is likely to be subjected.

I accomplish this object by the means shown in the accompanying drawing, in 45 which,

50 Figures 1 and 2 are central longitudinal sectional views on the line 1—1 of Fig. 3. Fig. 3 is a plan view of the device, Fig. 4 is a detail sectional view of the discharge nozzle.

According to my invention I provide a standpipe, or vertically disposed chamber α

having a threaded nipple b at its lower end, to which the water supply-pipe may be connected, and having a cap c for closing its 55 upper end. The lower end of the standpipe α is closed by a partition d , in which a supply-pipe e is mounted, said pipe extending through said partition d and opening at its lower end into said nipple b . Said pipe e 60 is extended upwardly within the standpipe α , and is bent at right angles so that it extends horizontally to the wall thereof, at which point it is reduced to provide an ejector nozzle e' . A bracket f , in the form of 65 a pipe, is mounted at one end in the wall of the standpipe α , adjacent its lower end and extends horizontally therefrom for a suitable distance, and a casing g is mounted on the end thereof, said pipe f preferably ex- 70 tending through the adjacent wall of said casing, abutting on the inner side of the opposite wall, and being securely soldered at both points, so that the casing is rigidly supported by said pipe. The lower portion 75 of said pipe f at its end, is cut away to provide an open passage f' between the interior thereof and the interior of the casing g . The lower end of the casing g is provided with an opening g' , and the walls of the 80 casing about said opening are preferably provided with slots g^2 , for a purpose to be explained.

A basin h is provided in the upper portion 85 of the casing g which is united to the latter at its rim, and this rim is made rounding so that overflowing water will run down the side of said casing. A jet pipe i is arranged within and extends centrally of the pipe f , and the intake end of pipe i passes through 90 the wall of the standpipe α , and has a flared end i' which opens therein in alignment with the nozzle e' , the latter extending for a short distance into the flared end of the pipe i but out of contact therewith to provide a 95 tapering annular space therebetween, the sides of the nozzle e' and the inner wall of the flaring end i^2 being approximately parallel and relatively constructed and arranged in the form of an ordinary water ejector, as 100 shown in Fig. 4. This annular space should have an area as great as the area of the nozzle e' , for reasons which will appear. The pipe i extends to the middle of casing g and

then extends vertically through the bottom of the basin *h* at its middle and terminates in a nozzle *i*² at a suitable distance thereabove, preferably a small fraction of an inch below the level of the rim of the basin.

An overflow pipe *j* is connected to the standpipe *a* adjacent its upper end, said pipe *j* extending obliquely downward and being connected to, and opening into the supporting pipe *f*, adjacent the casing *g*.

With the above described arrangement the operation is as follows:—A properly regulated supply of water is delivered to the nipple *b* and thence discharged through the nozzle *e'* into pipe *i*, the force of the discharge carrying the water through the pipe *i*, so that a jet is discharged through its nozzle *i'*. The basin *h* will immediately fill, so that the end of nozzle *i'* will be slightly submerged and the jet will be discharged through the water in the usual manner, as indicated in Fig. 1. If the water pressure is low, and, as the flow of the water is somewhat obstructed, some of the water discharged from the nozzle *e'* will pass back through the annular space between said nozzle and the entrance to the pipe *i*, and the water will back up in the standpipe *a* and partly fill the same. The overflow pipe *j* is connected to the standpipe at a point somewhat above the crest of the stream which is delivered from the nozzle *i'*, so that when the water level has been raised approximately to the level indicated in Fig. 1 in the standpipe, which is some distance below the point of connection of the overflow pipe *j*, thereto, it will not be raised any farther, as the head of water will then be sufficient to prevent back flow past the nozzle *e'*. In case, however, the water pressure is high, then the nozzle *e'* and flaring end *i'* will act as an ejector and will prevent accumulation of the water in the standpipe, air being drawn therefrom by the ejector and supplied thereto through the pipe *j*. Under all conditions of pressure sufficient to cause a jet to be discharged, the ejector action will be sufficient to decrease, to some extent, the height to which the water will rise in the standpipe, but, under none of these conditions will the water level be raised to an extent sufficient to cause the water to overflow into the pipe *j*. If, however, the nozzle *i'* should be obstructed, as indicated in Fig. 2, then the water will flow back past nozzle *e'* into the standpipe *a* and overflow into the pipe *j* and be discharged through pipe *f* and opening *f'* and through the opening *g'*.

The slots *g²* about the opening *g'* are provided to make it difficult, or practically impossible to defeat the object of the invention by obstructing the opening *g'* and then pressing the finger on the nozzle *i'*, said slots permitting the discharge of water in

case the opening *g'* is obstructed. Obviously openings in the walls of the casing *g* at any other points would accomplish the same result.

It may be observed that the pipe *j*, as arranged, acts as an effective brace for the pipe *f* in supporting the casing *g*.

I claim:—

1. A drinking-fountain comprising a water pipe having an upwardly directed drinking nozzle, a water chamber connected at its lower end to said supply-pipe and having an overflow opening above the level of the end of said nozzle, substantially as described. 75

2. A drinking-fountain comprising a standpipe, a jet pipe having its entrance end in said standpipe and having an upwardly directed discharge-nozzle, a water supply-pipe having its discharge end directed into the entrance end of said jet pipe and arranged to provide an opening therebetween to permit back flow into said standpipe when said nozzle is obstructed and an overflow for said standpipe above the level of 85 said discharge nozzle, substantially as described. 90

3. A drinking-fountain comprising a chamber having an outlet opening, a water ejector located in said chamber in position to withdraw the water therefrom, and a jet pipe having an upwardly directed discharge-nozzle terminating below the level of said outlet opening and into the inlet end of which said ejector is arranged to discharge, substantially as described. 95

4. A drinking-fountain comprising a water-chamber having an overflow opening and a water-ejector located in said chamber below said opening in position to withdraw 105 the water therefrom and having a discharge-pipe provided with an upwardly directed discharge nozzle terminating below the level of said overflow opening, substantially as described. 110

5. A drinking-fountain comprising a standpipe, a jet pipe having an upwardly directed discharge-nozzle at one end and connected at its inlet end to the lower portion of said standpipe, a water-supply pipe extending into said standpipe and having a nozzle at its end spaced from and arranged to direct a jet into said inlet end of said jet pipe, and means permitting the discharge of the water from said standpipe when the water therein has been raised to a certain level above said nozzle, substantially as described. 115 120

6. A drinking-fountain comprising a standpipe, a casing mounted thereon at one side thereof and having a basin in its upper portion, a jet pipe leading from said standpipe into said basin and having an upwardly directed nozzle therein, a water-supply-pipe leading into said standpipe and arranged to 125 130

direct the water into said jet pipe and to provide an open communication with said standpipe, and an overflow pipe leading from the upper end of said standpipe to 5 said casing beneath said basin, substantially as described.

In testimony whereof, I have signed my

name to this specification, in the presence of two subscribing witnesses.
